UNITED STATES PATENT OFFICE.

RUSSELL PHILLIPS, OF BOSTON, MASSACHUSETTS, ASSIGNOR OF ONE-HALF
TO WILLIAM H. ADAMS, OF SAME PLACE.

ELEVATOR.

SPECIFICATION forming part of Letters Patent No. 271,264, dated January 30, 1883.

Application filed October 11, 1882. (No model.)

To all whom it may concern:

Be it known that I, RUSSELL PHILLIPS, of Boston, in the county of Suffolk and State of Massachusetts, have invented certain new and useful Improvements in Elevators, of which the following is a specification.

My invention relates to freight and passenger elevators, and to safety attachments for the same, the objects being to lessen the expense of running and to increase the safety. I attain these objects by the mechanism illustrated in the accompanying drawings, in which—

Figure 1 is a side elevation, showing the principal parts of my elevator. Fig. 2 is a rear elevation of the same. Fig. 3 shows in side elevation that part of the driving gear and brake devices that is attached to the elevator-carriage. Fig. 4 is a plan view, showing that part of the driving-gear that is attached to the elevator-carriage. Figs. 5, 6, 7 are views to illustrate the regulator device for controlling the descent of the elevator.

In the drawings, A represents the platform of the elevator-carriage.

A' A² A³ A⁴ is the frame, attached to the under side of the same, which serves as a structure for attaching the operating parts.

B³, Figs. 1 and 2, represents a counterpoise weight, which is connected to the four corners of the elevator-platform A by means of ropes B B' B B', which pass over pulleys B² B².

Attached to the frame of the elevator-carriage is a shaft, F', which extends entirely across the elevator, and has at each end a pinion, F². (See Figs. 1 and 4.) These pinions F² engage with vertical ratchets F³, Figs. 1 and 4.

F is a grooved pulley running on a shaft, F', which is so arranged that it may revolve without turning the shaft F', or when desirable its revolution will cause the shaft F' to revolve. This is effected by a conical clutch device which connects it with the bevel-gear wheel F⁵, the said gear-wheel F⁵ being rigidly attached to the shaft F', so that when the grooved wheel F is in clutch-connection with F⁵, then the revolution of F will cause a corresponding revolution of the shaft F' and the pinions F², and cause the same to traverse the vertical ratchets F³, Figs. 1 and 4, which action causes a corresponding movement of the elevator-car-

riage. The grooved wheel F is moved in and out of clutch-connection with the wheel F⁵ by means of the collar G, Fig. 4, and lever K¹⁰, pivoted at K¹¹, this lever K¹⁰ being operated by an arm, K⁹, which extends radially from the piston-shaft K⁶, and operates in an inclined slot, G², made in the moving end of the lever K¹⁰. (See Fig. 4.) The groove-wheel F is caused to revolve by the revolution of the drive-wheel D, Figs. 1 and 2. This drive-wheel D is supported in suitable housings, as shown by D² D², Fig. 1, and may be driven by steam, water, or other power. Its motion is communicated to the groove-wheel F by means of the rope D³ D⁵ D⁶ D⁸ D⁹ D¹⁰ D¹¹ D⁴, which is arranged to pass over the several pulleys, H H' H² H³ H⁴ H⁵, (see Fig. 1,) the part D⁶ D⁷ passing round the groove-wheel F, so that any motion of the rope D³ D⁴, &c., will cause the groove-wheel F to revolve, and if the said groove-wheel F is in clutch-connection with the shaft F' it will cause the elevator-carriage to ascend.

The drive-wheel D is provided with an internal gear, Fig. 1, which engages with the pinion D', by which it may be driven.

E E', Fig. 1, is a pawl, which, engaging with the teeth of the internal gear, will prevent the wheel D from revolving in the wrong direction.

The moving parts already described are specially designed for raising the elevator-carriage, although they may be used, if required, for the purpose of lowering it; but I do not depend on this part of the apparatus for lowering the elevator-carriage, as I have designed special appliances for regulating the descent of the elevator-carriage, which I will now proceed to describe.

The beveled-gear wheel F³ drives a pinion-gear, F⁶, (see Figs. 3 and 4,) which is connected by a clutch and shaft, F⁷, to the crank-disk F⁸, Figs. 3 and 4. This clutch F⁷ is so arranged that when the elevator-carriage is going up the revolution of the beveled gears F⁵ F⁶ will not cause the crank-disk F⁸ to revolve; but when the carriage is coming down the revolution of the gears F⁵ F⁶ will cause the crank-disk F⁸ to revolve. Hence by regulating the velocity of this crank-disk I can regulate the velocity of the descent of the elevator-carriage and make the same perfectly safe. This I accomplish by connecting the crank-disk F⁸,

through the pin L, link L', and pin L², to the sliding cylinder L³, this cylinder traversing on the piston-rods K⁶ L⁴, Fig. 4, said piston-rods K⁶ L⁴ having no longitudinal motion. The piston-head within the cylinder L³ is compound—that is, it consists of two perforated disks L⁵ K⁷, the disk L⁵ being stationary, while the disk K⁷ may be partially revolved in connection with its rod K⁶. This partial revolution of the disk K⁷ opens or closes the aperture in the disk L⁵ in the same manner that an ordinary damper or register operates. Consequently if the cylinder L³ is filled with oil or any other suitable liquid the resistance offered to its rapid motion may be regulated by turning the disk K⁷, which, as already stated, diminishes or enlarges the means of communication from one end of the cylinder to the other. This adjustment of the disk K⁷ is effected by the lever K⁵, Figs. 3 and 4, said lever being connected to the shaft K⁶; as indicated at Figs. 3 and 4, so that by swinging this lever the shaft K⁶ and disk K⁷ are operated. This lever K⁵ may be also operated by means of the hand-rope K K' K² K³, Fig. 3, which runs the entire length of the well-room, being rigidly attached at both ends to stationary parts of the well-room structure, a part of this rope always being accessible to the occupant of the elevator-carriage. As this rope K K' K² K³ passes round a pulley, K⁴, attached to the hand-lever K⁵, it is manifest that if the said rope is pulled it will draw the lever in the direction of the arrow R, Fig. 3, and thus operate all of the parts cinematically connected to it. This lever K⁵ is held back by the springs S, Figs. 3 and 4.

As an additional safety device for regulating the descent of the elevator, I use a frictional brake, P, Fig. 3, placed within a recess or sinkage turned in the face of the wheel F⁵, the end of the brake bearing against the circumscribing outer wall, P', of the recess, and is held in contact by the indirect action of the springs S and S' when not drawn out of contact by the movement of the lever P², which is pivoted at

P³, Fig. 3, the lever P² being operated in its turn by a projection at k' formed in the inner side of the lever K⁵, so that as the lever K⁵ is thrown over in the direction of the arrow R its action, through the projection k', against the under side of the lever P² at the point P⁴ will lift up this end of the lever P², and thus throw down the brake P, connected with its other end.

N, Figs. 4 and 7, is a tube for furnishing oil for the cylinder L³. (See Figs. 4 and 7.) This feed-tube N (see Fig. 7) is provided with a closing-cap, N', and with a check-valve, N², as shown.

I claim—

1. The combination of the drive-wheel D, rope D³ D⁵ D⁶ D⁷ D⁸ D⁹ D¹⁰ D¹¹ D⁴, the wheel F, shaft F', and pinions F² with the elevator-carriage A and vertical racks F³, all arranged to operate substantially as described, and for the purpose set forth.

2. In an elevator, the combination of the grooved wheel F, adapted to clutch with the gear-wheel F⁶, and the shaft F', with the clutch-operating device consisting of the collar G, lever K¹⁰, slot G², arm K⁹, shaft K⁶, and lever K⁵, all operating together substantially as described, and for the purpose set forth.

3. In an elevator, the combination of the lever K⁵ and the parts operated by it with the pull-cord K K' K² K³, all substantially as described, and for the purpose set forth.

4. In an elevator, the combination of the gear-wheel F⁵ F⁶, clutch-shaft F⁷, crank-disk F⁸, link L', and cylinder L³ with the piston-rods K⁶ L⁴ and adjustable piston-disk K⁷ L⁵, all operating together substantially as described, and for the purpose set forth.

5. The combination of the wheel F, the brake P, and lever P² with the lever K⁵, provided with a projection, P⁴, all operating together substantially as described, and for the purpose set forth.

RUSSELL PHILLIPS.
